UNITED STATES PATENT OFFICE.

ALFRED SCHÄR, OF GOSSAU, SWITZERLAND.

AUTOMATIC GRINDING MILL.

Application filed February 20, 1925, Serial No. 10,590, and in Switzerland April 17, 1924.

The present invention relates to improvements in grinding mills and has for its object to provide a self-contained automatic grinding mill for domestic use to which the uncleaned wheat is supplied and the finished flour and brans are delivered into bags without involving any manual labour during this conversion.

Automatic mills for domestic use have already been proposed. However, they have the drawback that although they work automatically they do not produce a flour of the same quality as produced by the large mills. A flour of this quality requires the use of a large number of grinding passes and sifting means, and the self-contained automatic mill according to the present invention is so designed that it is possible to house all the means for providing the required number of grinding passes, so that the automatic mill is of a size which permits its use for domestic purposes, and yet produces a flour that equals that obtained in large mills. A mill of this type is of particular importance for farmers, who are thereby enabled to produce their own flour and of a quality which only a large mill has hitherto been able to supply.

The self-contained automatic grinding mill according to the present invention comprises a number of cooperating cylinder grinding surfaces for rough grinding, a number of cooperating cylinder grinding surfaces for fine grinding, and a first set of sifting means arranged above and cooperating with the rough grinding cylinder surfaces and a second set of sifting means arranged above the fine grinding surfaces. Further means are provided for conducting the material to be ground consecutively to said individual cylinder grinding surfaces for rough and for fine grinding and to and from said sifting means, said means including a number of elevators arranged between the rough grinding rolls and the fine grinding rolls and to which the material leaving said individual cylinder grinding surfaces is conducted and which deliver said material to said sifting means. These sifting means are arranged on both sides of the elevators, whereby a plurality of grinding passes are provided in a mill that requires a minimum of space.

Other features of the automatic mill will be referred to in the following description of a constructional example.

The automatic mill according to the present invention is illustrated by way of example on the accompanying drawings, in which:—

Fig. 1 is a front elevation of the automatic mill with parts shown in section,

Fig. 2 is a side elevation seen from the right hand side of Fig. 1,

Fig. 3 is a side elevation seen from the left hand side of Fig. 1 and showing the drive of various parts of the automatic mill,

Fig. 4 is a vertical section along line IV—IV in Fig. 1,

Fig. 5 is a vertical section along line V—V in Fig. 4,

Fig. 5a is a horizontal section of a detail,

Fig. 6 is a vertical section along line VI—VI in Fig. 4,

Fig. 7 is a vertical section along line VII—VII in Fig. 4,

Fig. 8 is a horizontal section along line VIII—VIII in Fig. 4,

Fig. 9 is a horizontal section along line IX—IX in Fig. 4,

Fig. 10 shows a part of the mill in a vertical section along line X—X in Fig. 9,

Fig. 11 is a vertical section along line XI—XI in Fig. 9,

Fig. 12 is a vertical section along line XII—XII in Fig. 9,

Fig. 13 shows a detail in section;

Figs. 14—16 show the parts used for feeding the stripping machine in vertical section,

Fig. 17 is a vertical section along line XVII—XVII in Fig. 15,

Fig. 18 shows details of the sifter mechanism in a vertical section and

Fig. 19 is a diagram showing the various passages of the material to be ground in the automatic mill. Referring now to the drawings 1 and 2 denote the cooperating fluted rollers of the rough grinding device and 3 and 4 are the cooperating smooth rollers of the fine grinding device. The rollers 2 and 4 are rotated at a higher speed than the rollers 1 and 3. The shafts 5 and 6 of the lower quick running rollers 2 and 4 are mounted in fixed bracket bearings 7 and 8 respectively (Fig. 2) and the shafts 9 and 10 of the upper rollers 1 and 3 are mounted in bracket bearings 11 and 12 swingably arranged about pivots 13 and 14 respectively. The bearings 11 and 12 respectively are resiliently held in position by means of the

springs 15, 16 and 17, 18 respectively; hand-wheels 19 and 20 cooperating with nuts 21, 22 on the ends of screw threaded bolts 23 and 24 serve to adjust the distance between the shafts 5 and 9 and 6 and 10 respectively whereby the distance between the circumference of the cooperating rollers 1 and 2 and 3 and 4 respectively can be adjusted to obtain a desired crushing and grinding effect. Both pairs of rollers extend substantially across the whole width of the chest 25 which encloses the whole automatic mill. The base part of the chest is reinforced by the part 26, the upper face of which serves as support to the fixed bearings 7 and 8.

The pair of rollers 1 and 2 is subdivided in the longitudinal direction into seven individual pairs of roller surfaces 27, 28, 29, 30, 31, 32 and 33 (Fig. 6) forming seven different passages and the fineness of the fluting increases from the pair of roller surfaces 27 to 33. Partition walls 34, 35, 36, 37, 38 and 39 separate these passages from each other.

The pair of rollers 3 and 4 for fine grinding is subdivided into five individual pairs of roller surfaces 40, 41, 42, 43 and 44, forming five passages for fine grinding, which passages are separated from each other by the partition walls 45, 46, 47 and 48.

The drive of the automatic mill is effected by means of a main driving pulley 49 (Fig. 1) fixed to a short piece of shaft 50 mounted in bearings 51 and 52. To the shaft 50 a chain wheel 53 (Fig. 3) and a gear wheel 54 are fixed, the latter cooperating with a gear wheel 55 on a short counter shaft 56. The rotation of the roller shaft 5 is obtained by a chain wheel 57 fixed to said shaft and a chain 58 operatively connecting the chain wheels 54 and 57. A further chain wheel 59 is fixed to the shaft 5 and cooperates with a chain wheel 60 fixed on the roller shaft 10 by means of the chain 61, whereby rotation is imparted to the shaft 10 and thereby to the roller 3. On the countershaft 56 a chain wheel 62 is fixed which cooperates with a chain wheel 64 on the roller shaft 6 through the intermediary of the chain 65 and the roller shaft 9 is driven from the roller shaft 6 by means of the chain 66 and the chain wheels 63 and 67.

A chain wheel 68 on the shaft 6 drives by the chain 69 a chain wheel 70 on a shaft 71. On the shaft 102 a screw wheel 72 (Figs. 14 and 17) is fixed as well as a crank pin 73. The screw wheel 72 is in mesh with a screw wheel 74 on a shaft 75 and a screw wheel 76 fixed to a shaft 77 cooperates with the screw wheel 76. A bevel wheel 78 is fixed to the shaft 77 and is in mesh with a bevel wheel 79 on a vertical shaft 80 of a stripping device. The latter comprises vertical beaters

81 by which the grain is projected against a perforated drum 82 in the known manner. The husks of the grain pass, through the drum and leave the mill at the aperture 83 and the stripped grain leaves at the bottom 70 of the drum 82 and passes into the channel 84.

The material to be ground, i.e. the grain, is fed into the hopper 85 from where it passes a preliminary sieve 86, by which the 75 large sized impurities are separated which leave at 87, and the material passing the sieve 86 drops on a further sieve 88 through which sand and other impurities pass. The sieves 86 and 88 are shaken to and fro from the crank pin 73 and a connecting rod 89 and are suspended on plate springs 90 and 91. The sand passing through the sieve 88 is deviated by partition walls such as 92 (Fig. 16) and leaves at 83, and the grain, which 85 is retained by the sieve 88 passes through the duct 93, in which a magnet 94 is provided, into the afore-mentioned stripping device 81, 82.

Above the rough grinding rollers 1, 2 and the fine grinding rollers 3, 4 sifters 95, 96, 97 and 98 are arranged which consist of a circular casing 99 one portion of which is formed by a sieve 100. Inside the casing a number of blades 101 are continuously rotating about the shafts 102 of the sifter 95 or the shafts 103, 104 and 71 of the sifters 96, 97 and 98. The shaft 104 is rotated by means of a chain 105 and chain wheels 106 and 70' from the shaft 71 and to the shafts 102 and 103 100 rotation is imparted by means of chains 107 and 108 and chain wheels 109, 109' and 110 (see Fig. 3).

In Fig. 18 the sifters 97 and 98 are shown in a vertical section from which it may be 105 seen that the sifter 97 is subdivided and consists of four individual sifters 111, 112, 113 and 114 and the sifter 98 consists of three individual sifters 115, 116 and 117. In a similar manner the sifter 96 is subdivided into four individual sifters 118, 119, 120 and 121 and the sifter 95 consists also of four individual sifters 122, 123, 124 and 125 as is indicated in Fig. 19. The sifters 111, 112, 113 and 114 are subdivided by partition 110 walls 126, 127 and 128 and partition walls 129, and 130 separate the sifters 115, 116 and 117 from each other (Fig. 18). The partly crushed or ground material consisting of semolina or a mixture of meal and semolina to be sifted enters the sifter 111 through the aperture 131 arranged at one end of the sifter. The material which does not pass the sieve 100 leaves the sifter 111 through the aperture 132 arranged at the opposite 125 end of the sifter. Similar inlet openings 133, 134, 135, 136, 137 and 138 and outlet openings 139—144 are provided in the sifters 112—117 (Figs. 7 and 18). The corresponding inlet openings in the sifters 118—125 are 130

145—152 and the outlet openings are 153—160 (Figs. 6 and 19). One of the blades 101 in each sifter consists of a number of single parts 101' (Fig. 18) arranged at an angle 5 to the axis of rotation of the blades whereby the material inside the sifter is moved from the inlet end towards the discharge end.

The material is delivered to the individual sifters by means of bucket elevators 10 of which fifteen are provided arranged beside each other. Of these the elevators 161—169 (Figs. 8 and 19) discharge towards the sifters 118—125 and the elevators 170—175 discharge towards the sifters 15 111—117. The cooperation of every single elevator with the single sifters will be explained later on with reference to Fig. 19 which shows a diagram of the various passages of the material automatically occurring 20 within the mill. The elevators are driven by imparting rotation to their upper pulley shafts 176 and 177. To this end a chain pulley 178 is fixed to the shaft 177 and a chain 179 transmits the driving 25 power from the shaft 103. A pair of meshing spur gear wheels 180 and 181 is interposed between the shafts 176 and 177. Each elevator is enclosed in a casing and it receives the material to be raised to 30 the top of the mill from one of the individual rough grinding rollers or fine grinding rollers or from another source as will be explained hereinafter with reference to the diagram shown in Fig. 19. As is shown 35 in Figs. 6, 7 and 9 for instance the material passing through the rough grinding passage 27 is supplied to the elevator 161 through an opening 182; the elevator 162 receives the material which has passed the stripping device 81, 82 through the chute 84 and the opening 183; the elevator 163 receives the material leaving the rough grinding passage 28 through the chute 184; the elevator 164 receives the material from the rough grinding 40 rollers 29 through the chute 185, to the elevators 165, 166 and 167 material is supplied from the roller passages 30, 31 and 32 through the chutes 186, 187 and 188; the elevators 170, 171, 172, 173 and 175 are fed by 45 the material from the fine grinding roller passages 44, 43, 42, 41 and 40 respectively through the chutes 189, 190, 191, 192 and 193 respectively; the elevator 174 is supplied with material through chute 194 coming 50 from the rollers 33. The elevator 169 receives the material from two different sources as is shown in Figs. 10 and 11 through chutes 195 and 196.

The material which passes through the 55 sieve portions 100 of the sifters 95 and 96 falls into a screw conveyor 197 extending across the whole width of the mill from where it passes through the chutes 198, 195 to the elevator 169 (Fig. 10). The screw conveyor 197 is driven from the shaft 9 by

means of the chain 199 and the chain wheel 200. Below the sifters 97, 98 two screw conveyors 201 and 202 are arranged which receive the material which passes the sieve parts 100 of some of the individual sifters 70 111—117. The material discharged by the screw conveyors 201 and 202 is the finished meal obtained in two qualities and leaves the mill at the discharge openings 203 and 204 (Figs. 1 and 2) to be filled into bags. The 75 conveyor 201 is driven from the shaft 10 by means of the chain 205 and chain wheels 206 and 206' (Fig. 3) and the conveyor 202 is in driving connection with the conveyor 201 by the pair of cooperating gear wheels 80 207 and 208 (Fig. 9).

209 denotes a feed roller arranged above the fine grinding roller 3, a small roller 210 cooperates with the roller 209. The latter is driven by the aid of a chain wheel 211 85 and a chain 212 from the chain wheel 211' on the shaft of the screw conveyor 201.

In order to keep clean the sieve parts 100 of the sifters 97 and 98 brushes 213 are provided which are in contact with the sieve 90 parts 100 and are mounted on a frame 214 (Fig. 4). On the latter further brushes 215 are provided which cooperate with windows 216. The frame 214 is fixed to a rod 217 extending across the whole width of the 95 mill. The rod 217 can be reciprocated longitudinally in the bearings 218 and a to and fro movement is imparted to the rod by means of a connecting rod 219 and crank 220. The latter is rotated, Fig. 1, by means 100 of a worm wheel 221 cooperating with a worm 222. The drive of the worm is effected by a pair of gear wheels 223, 224, chain wheels 225, 226, chain 227 from a counter shaft 228. The latter drives by 105 means of a pair of gear wheels 229 and 230 a shaft 231 and is driven from the elevator shaft 177 through the interposition of chain wheels 232, 233 and chain 234, of a train of gear wheels 235, 236, 237 and 238, the chain 110 wheels 239 and 240 and chain 241 as is shown in Fig. 2. The chain wheel 239 and gear wheel 238 are fixed to the shaft 242 which will be referred to later on.

The materials leaving some of the sifters 115 118—125 have to pass plane shaking sieves before they are delivered for further treatment. These shaking sieves (Figs. 4 and 5) are enclosed in a chest 243 arranged at one side of the mill casing 25. There are two 120 sieves 244 and 245 slightly inclined against the horizontal and arranged beside each other at different elevations and mounted in a box 246 which is suspended on two plate springs 247 and 248. Above the sieves 125 a trough 249 is arranged through which other material is discharged at its lower end which leaves the chest 243 at the opening 250. The material which passes through the sieves 244 and 245 drops on a bottom 130

251 and passes through an opening 252 of the latter from where it gets down a chute 253 to the elevator 168. The coarser material which does not pass through the 5 sieves 244 and 245 is discharged at the lower end 254 of the latter and is conducted by the bottom 255 to a chute 256 and thereby to the elevator 166. The shaking motion of the chest 246 and thereby of the sieves 10 244 and 245 is effected by means of a connecting rod 257, and crank gear 258 which is rotated by the aid of screw wheels 259, 260, chain wheels 261, 262 and chain 263 from the shaft of the screw conveyor 197 15 (Fig. 3). The sieves 244 and 245 may be cleaned by a known travelling brush 264 diagrammatically indicated in Figs. 4 and 5 and supported by a sieve 244'.

Above the stripping device (Figs. 16 and 20 17) a bran brushing device is arranged consisting of a circular perforated drum 265 in which brushes 266 which are in contact with the drum 265 are rotated by the shaft 75. The material is fed through the opening 267 25 from the outlet opening 144 of the sifter 117. The material passing the drum sieve 265 is discharged from the mill through the opening 268 and the material which does not pass the drum leaves the latter at 30 the opening 269 and is discharged at 270. In order to convey the latter material by means of the brushes to the opening 269 arranged at one end of the drum, the brushes consist of individual parts 266' which are 35 placed obliquely to the direction of the axis of rotation of the brushes.

In order to remove the hot air generated 40 inside the mill an exhaust fan 271 is arranged on the top of the chest 25. Rotation is imparted to the fan 271 from the shaft 104 (Fig. 3) by means of the chain 45 wheels 272, 273 and the chain 274. To prevent dust from being discharged by the fan two chests 275 and 276 are provided on the top of the chest 25, which contain a 50 number of hose filters. There are eight filter cylinders 277—284 provided in each of the chests 275 and 276, the end hose 277 and 284 are in compartments to themselves, 55 285 and 286 and the remaining six hose are arranged in pairs within the chambers 287, 288 and 289 (Figs. 1 and 4). The inner part of the chests 275 and 276 is subdivided by a horizontal partition wall into an upper compartment 290 and a lower compartment 291 (Fig. 4). Inside the compartments 290 the mechanism for shaking the 60 hose filters is arranged which consists of the shaft 231 in the chest 276 and the shaft 242 in the chest 275 on which shafts cam discs 293 are fixed. The upper end of each hose is fixed to a two-armed lever 294 turnable about 295; a compression spring 296 acts on the vertical arm of said lever 65 and causes a tightening of the hose in their

longitudinal direction. With the free end of the vertical arm of the lever 294 two teeth 297 and 298 on the cam disc 293 co-operate. Further a cam face 299 is provided on one side of the cam disc 293 which face cooperates with a pin 300 fixed to a gate 301 pivoted at 302. The gate 301 controls an opening 303 provided between the compartments in which the hose filters are located and the compartment 291. A detail 75 of the gates 301, which are held in their open position by tension springs 304, is shown in Fig. 13. Further a conduit 305 passes through the compartment 291 and connects the compartments in which the 80 hose filter are located with the surrounding atmosphere. The flow of air through said conduits is also controlled by the gates 301. The lower open ends of the hose are connected to openings 306 (Fig. 4) leading 85 to chutes 307 returning the meal collected in the hose to the elevators; the chutes serve at the same time as conduits for leading the hot air from the interior of the mill to the 90 hose filters, one chute 307 being provided for every two hose filters.

The operation of the above described filter plant is the following:

The suction side of the fan 271 is connected by the conduit 308 with the compartments 291. The warm air is sucked from the interior of the mill through the hose filters in those compartments in which the gate 301 has not closed the opening 303. The dust and meal contained in the 100 air is deposited in the hose filters. In order to clean the filters the teeth 297 and 298 of the rotating cam disc 293 act upon the vertical arm of the two armed lever 294 whereby the hose is slackened and the spring 296 105 is compressed. When the end of the lever arm glides off a tooth the compressed spring suddenly turns the lever 294 in the upward direction and causes a tightening of the previously slackened hose filter whereby the 110 material adhering to the hose is shaken off. To enhance this cleaning action the gate 301 which closes the opening 303 uncovers at the same time the conduit 305 so that air from outside passes through the hose when 115 the latter is cleaned and this fresh air gets into the interior of the mill where it cools the grinding rollers. The cam discs 293 are angularly displaced one against the other so that the cleaning of the various hose filters 120 occurs consecutively.

Now the passages which the grain has to take within the mill shall be explained with reference to the diagram illustrated in Fig. 19.

The grain is filled into the hopper 85 and has to pass through the sieve 86 and along the sieve 88. The coarse impurities are discharged at 87 and the sand and small matter passing through the sieve 88 are discharged 130

at 83 from the surrounding space 83' (Figs. 14-17). The cleaned grain enters the stripping device, the husks pass through the drum 82 and are discharged at 83, while the stripped grain passes through the chute 84 (Figs. 5 and 9) into the elevator 162. The latter lifts the grain to the top of the mill and discharges it into the chute 309 (Fig. 6) whereby it is delivered to the rough grinding rollers 27, and after being preliminarily crushed thereby it passes the chute 182 (Fig. 6) to the elevator 161. The latter discharges the material through the opening 145 into the sifter 118 and the part 10 of the material which does not pass the sieve of the shifter 118 leaves the latter at the opening 153 and falls down to be crushed a second time by the rollers 28. On leaving the latter it passes through the chute 184 and gets to the elevator 163 by which it is discharged into the inlet opening 149 of the sifter 122. The part of the material which is still in the state of a coarse semolina and which does not pass 15 through the sieve of the sifter is discharged at 157 and is further treated by the rollers 29, and falls thereafter through the chute 185 to the elevator 164. The latter delivers the material to the inlet opening 146 of the sifter 119, the coarser parts leave the latter at the discharge opening 154 from where they pass to the rollers 30 to be further crushed. Then the material falling down 20 the chute 186 is raised by the elevator 165 and delivered through the opening 150 to the sifter 123. The parts which do not pass the sieve of the sifter are discharged at 158 onto the rollers 31, leave the latter through the chute 187 to be raised by the elevator 166 which delivers it through the opening 147 into the sifter 120. The material leaving 25 the latter at 155 is now crushed a sixth time by the rollers 32, and gets by way of the chute 188 to the elevator 167 which delivers it through 151 into the sifter 124. The material leaving the sifter through 159 consists solely of bran and is delivered 30 through the chute 310 (Fig. 5) to the trough 249 from where it is directly fed into bags at 250.

The finer semolinas which have passed through the sieves of the sifters 118, 119, 120, 122, 123 and 124 fall into the screw conveyor 197 (see Fig. 4) from which they are delivered to the chutes 198 (Fig. 10) and 195 and thereby to the conveyor 169 which discharges this material at 148 into the sifter 121. The material which does not pass 35 through the sieve of the sifter leaves the latter at 156 and enters directly the lower sifter 125 at 152 (Fig. 6) and is discharged at 160 down a chute 311 (Fig. 5) to the shaking sieve 244. The material travelling along the sieve 244 gets into the chute 256 and to the elevator 166 (Fig. 5), which

returns it to the sifter 120 and this material has to pass once more the rollers 32. The material which has passed the sieves of the sifters 121 and 125 is led through the chute 312 to the shaking sieve 245 from 70 where it is led together with the material which has passed through the sieve 244 by the chute 253 (Fig. 5) to the elevator 168 which feeds it directly to the rollers 33 by which the final rough grinding is finished. 75

From the rollers 33 the material is conducted to the elevator 174 which delivers it to the sifter 111 at 131. The material which does not pass the sieve of the sifter 111 leaves the latter at 132 and is conducted to the fine grinding rollers 40, falls down the chute 193 to the elevator 175 (Fig. 7) which delivers it at 136 to the sifter 115. The material leaving the latter at 142 gets to the rollers 41, then down the chute 192 80 (Fig. 7) to the elevator 173, at 133 into the sifter 112, leaves the latter at 139 enters directly into the sifter 116 at 137, leaves the latter at 143 and gets to the next roller passage 42. From here the material falls down the chute 191 to the elevator 172 and is delivered by the latter at 134 into the sifter 113, leaves the latter at 140 to be further treated by the rollers 43. On leaving the latter the material gets via the chute 190 to the elevator 171, enters at 135 the sifter 114, leaves it at 141 and is ground for the last time by the rollers 44. The rest of the treated material falls down the chute 189 85 to the elevator 170 which delivers it at 138 to the sifter 117, it leaves the latter at 144 and enters at 267 the drum 265. The fine parts brushed through the drum are collected at 268 as coarse meal for feeding animals and the material which does not pass 90 the drum is collected at 270 and consists of clean bran. 95

The finished meal, which passes the sieves of the sifters 111-117 is obtained in two qualities. To this end the meal passing the sieves of the sifters 111, 112, 115 and 116 is allowed to fall into the screw conveyor 201 which delivers it to the opening 203 for being filled into bags and the meal passing the sifters 113, 114 and 117 gets into the screw conveyor 202 and at the opening 204 into bags. 100

It will thus be seen that the function of the mill from the time when the uncleaned grain is filled into a hopper until the finished meal leaves the mill is entirely automatic, no manual labour being required during the conversion of the grain into meal. This conversion is obtained gradually and the material to be ground has to pass a comparatively large number of consecutive grinding and disintegrating passages. Every time before the material is subjected to a further grinding action, it has to pass 110 a sifting device which retains the parts of 115

the material which are already sufficiently fine and which do not require to pass the next grinding passage. In this manner the grinding is effected very economically, little driving power is required, first class products are obtained owing to the gradual grinding action, which moreover converts every particle of the grain, which can possibly be so converted into meal.

10 The number of passages for the material to be ground may obviously be different to that described with reference to the specific example.

I claim:

15 1. In a self-contained automatic grinding mill, particularly for domestic use, in combination; a number of cooperating individual grinding rolls for rough grinding, a number of cooperating individual grinding rolls for fine grinding, a set of sifting means arranged above the rough grinding rolls and cooperating with the latter, a second set of sifting means arranged above the fine grinding rolls and cooperating with the latter, and means adapted to conduct the material to be ground consecutively to said grinding rolls for rough and fine grinding and to and from said sets of sifting means, said means including a number of elevators arranged between said rough grinding rolls and said fine grinding rolls and to which the material leaving said individual rolls is conducted and which deliver said material to said sifting means arranged on both sides of the elevators.

20 2. In an automatic domestic grinding mill, in combination, a chest, rollers for rough grinding rotatably mounted in the lower part to one side of the vertical central plane of said chest and subdivided into a plurality of pairs of rollers, rollers for fine grinding rotatably mounted in the lower part to the other side of the vertical centre plane of said chest and subdivided into a plurality of pairs of rollers, sifters of the centrifugal type arranged vertically above said rollers for rough grinding and sifters arranged vertically above said rollers for fine grinding, and means adapted to conduct the material to be ground consecutively to said individual pairs of rollers of both types and to and from said sifters, said means including a plurality of elevators arranged in the middle portion of said chest, the material leaving said individual pairs of rollers being conducted to said elevators which deliver the material to said sifters, some of the elevators discharging to the sifters at one side of the casing and other elevators discharging to the sifters on the other side thereof.

25 3. In an automatic grinding mill, in combination, a chest, rollers for rough grinding rotatably mounted in the lower part and to one side of the vertical centre plane of said chest and subdivided into a plurality of individual pairs of rollers, rollers for

plane of said chest and subdivided into a plurality of individual pairs of rollers, rollers for fine grinding rotatably mounted in the lower part to the other side of the vertical centre plane of said chest and subdivided into a plurality of individual pairs of rollers, a plurality of sifters of the centrifugal type arranged vertically above said rollers for rough grinding and a plurality of sifters of the centrifugal type arranged vertically above said rollers for fine grinding, shaking sieves for cleaning the material to be ground, a stripping device for treating the cleaned material received from said sieves, and means to conduct the material to be ground consecutively to said individual pairs of rollers of both types and to and from said sifters, said means including a plurality of elevators arranged in the middle portion of said chest, the material leaving said individual pairs of rollers being conducted to said elevators which deliver the material to said sifters, some of the elevators discharging to the sifters on one side and other elevators discharging to the sifters on the other side of said casing.

4. In an automatic grinding mill, in combination, a chest, rollers for rough grinding rotatably mounted in the lower part and to one side of the vertical centre plane of said chest and subdivided into a plurality of individual pairs of rollers, a pair of rollers for fine grinding rotatably mounted in the lower part to the other side of the vertical centre plane of said chest, and subdivided into a plurality of individual pairs of rollers, a plurality of sifters of the centrifugal type arranged vertically above said rollers for rough grinding and a plurality of sifters of the centrifugal type arranged vertically above said rollers for fine grinding, shaking sieves for cleaning the material to be ground, a stripping device for treating the cleaned material received from said sieves, and means to conduct the material to be ground consecutively to said individual pairs of rollers of both types and to and from said sifters, said means including a plurality of elevators arranged in two sets beside each other in the middle portion of said chest, the material to be treated by the rough grinding rollers and the sifters on the same side of the chest being handled by the elevators of one set and the material to be treated by the fine grinding rollers and the sifters on the same side of the chest being handled by the elevators of the other set.

5. In an automatic grinding mill, in combination, a chest, rollers for rough grinding rotatably mounted in the lower part and to one side of the vertical centre plane of said chest and subdivided into a plurality of individual pairs of rollers, rollers for

- fine grinding rotatably mounted in the lower part to the other side of the vertical centre plane of said chest, and subdivided into a plurality of individual pairs of rollers, a plurality of sifters of the centrifugal type arranged vertically above said rollers for rough grinding and a plurality of sifters of the centrifugal type arranged vertically above said rollers for fine grinding, and means adapted to conduct the material to be ground consecutively to said individual pairs of rollers of both types and to and from said sifters, said means including a plurality of elevators arranged in two sets beside each other in the middle portion of said chest, the material to be treated by the rough grinding rollers and the sifters on the same side of the chest being handled by the elevators of one set and the material to be treated by the fine grinding rollers and the sifters on the same side of the chest being handled by the elevators of the other set, a filter plant consisting of several elements arranged on the top of said chest, and provided with an exhaust fan for removing the hot air inside the chest, and means for admitting fresh air to the interior of the chest, said means being controlled by means effecting a cleaning of said filter elements. 55
- 5 60
6. In an automatic grinding mill, in combination, a chest, rollers for rough grinding rotatably mounted in the lower part and to one side of the vertical centre plane of said chest and subdivided into a plurality of individual pairs of rollers, rollers for fine grinding rotatably mounted in the lower part to the other side of the vertical centre plane of said chest, and subdivided into a plurality of individual pairs of rollers, a plurality of sifters of the centrifugal type arranged vertically above said rollers for rough grinding and a plurality of sifters of the centrifugal type arranged vertically above said rollers for fine grinding, shaking sieves for cleaning the material to be ground, a stripping device for treating the cleaned material received from said sieves, and means to conduct the material to be ground consecutively to said individual pairs of rollers of both types and to and from said sifters, said means including a plurality of elevators arranged in two sets beside each other in the middle portion of said chest, the material to be treated by the rough grinding rollers and the sifters on the same side of the chest being handled by the elevators of one set and the material to be treated by the fine grinding rollers and the sifters on the same side of the chest being handled by the elevators of the other set, a filter plant consisting of several elements arranged on the top of said chest, and provided with an exhaust fan for removing the hot air inside the chest, and means for admitting fresh air to the interior of the chest, said means being controlled by means effecting a cleaning of said filter elements. 65
- 10 70
7. The method of grinding grain in a single apparatus, comprising cleaning the grain and rejecting the dirt, grinding the grain in a plurality of successive coarse grinding operations, sifting the material between successive grinding operations, returning the siftings from the coarse grinding operations to a last stage of coarse grinding, subjecting the resulting semolina to successive fine grinding, sifting the material intermediate each fine grinding, separating the fines from the fine grinding into graded flour, and grading the resultant coarse product, all of which operations are automatically performed, from the entrance of the grain into the machine to the delivery of the final products. 75
- 15 80
8. The method of grinding grain in a single apparatus, comprising cleaning the grain and rejecting the dirt, grinding the grain a plurality of times in a plurality of successive coarse grinding operations, raising the material and sifting after each coarse grinding operation preparatory to regrinding, subjecting the resulting semolina to successive fine grindings, lifting the resulting material and sifting it after each fine grinding, all the grinding steps being substantially at the same level, and the material being raised from substantially the same level to substantially the same level, and ventilating along the paths of lift to 90 maintain a current of cooling air past the grinding points. 95
